United States Patent Office.

ALONZO ARMSTRONG AND ALEXANDER WELLER, OF BUFFALO, NEW YORK.

Letters Patent No. 76,877, dated April 21, 1868.

IMPROVEMENT IN SLEIGHS.

The Schedule referred to in these Letters Patent and making part of the same.

TO ALL WHOM IT MAY CONCERN:

Be it known that we, ALONZO ARMSTRONG and ALEXANDER WELLER, of the city of Buffalo, in the county of Erie, and State of New York, have invented a certain new and useful Improvement in Bob-Sleigs; and we do hereby declare that the following is a full and exact description thereof, reference being had to the accompanying drawings, in which—

Figure I is a side elevation of a bob-sleigh provided with our improvement.

Figure II is a rear elevation of the same.

Like letters of reference designate corresponding parts in both figures.

The nature of our invention consists in connecting the front and rear bobs together by a curved reach, to allow the front bob to pass under the reach in turning, when said curved reach is used in combination with pendent links and hangers, and elevated standards for connecting the rear bob to the sleigh-body, so that the action of the reach may not prevent the free oscillation of the rear bob.

In the drawings, A is the box or body of the sleigh; B B the rear "bob," or runners; c c, two pendent brackets, firmly fastened to the under side of the box; D D, two supports or standards, secured by bracing or otherwise to the "bob," and of any suitable form or construction that will permit the hinging or jointing of the links or connecting-arms e e at their top, and be sufficiently strong to support the rear end of the sleigh-body, which is sustained by jointing the lower ends of the said links and pendent arms c c. H represents the curved reach connecting the front and rear pair of bobs together, the jointing of the reach to the front bobs, shown at H', being above the turn-table, upon which the front end of the sleigh-body rests, and the jointing at i to the rear bobs being sufficiently low to insure a proper line of draught thereto, while the curvature of the reach allows the front bob to pass under it in the turning of the sleigh.

When two pairs of runners are connected by a reach, the inclination of either pair in passing over inequalities causes a kind of oscillating motion backwards and forwards of the upper portion of the "bobs." The connection between the two pairs of runners being unyielding, it is evident that any change in the inclination of either pair will produce a change in the relation of any two points on top of the respective "bobs," causing them to slightly approach or recede from each other. Where both pairs of runners are connected to the box or body of the sleigh at any two fixed points, as in the ordinary construction, it is manifest that this relative change in those points cannot take place, (except in a slight degree, which the looseness of the joints or connections may permit,) and, as a necessary consequence, the free and natural movement of the runners is prevented.

And, further, it is necessary that the joints at the connection of the reach to both the front and rear bobs should lie in the same horizontal line, otherwise the slackness of the joints could allow only the slightest possible oscillation of the rear bob, so that the curved reach, involving a connection to the front bob above the turn-table, could not possibly be used with the ordinary mode of supporting the sleigh-body upon the rear bob; hence the necessity of using the pendent links, brackets, and standards above described for supporting the sleigh-body, to permit the free oscillation of the rear bob when the curved reach is used.

What we claim as our invention, is—

The combination of the curved reach H with the pendent links, hangers, and elevated standards for supporting the sleigh-body upon the rear bob.

ALONZO ARMSTRONG,
A. WELLER.
